UNITED STATES PATENT OFFICE.

FRIDOLIN SCHNELLE, OF WEST HOBOKEN, NEW JERSEY.

EMBROIDERING-MACHINE.

SPECIFICATION forming part of Letters Patent No. 335,094, dated January 26, 1886.

Application filed September 12, 1885. Serial No. 176,916. (No model.)

To all whom it may concern:

Be it known that I, FRIDOLIN SCHNELLE, of West Hoboken, in the county of Hudson and State of New Jersey, have invented a new and useful Improvement in Embroidering-Machines, of which the following is a full, clear, and exact description.

This invention relates to certain new and useful improvements in the Heilman embroidery-machine, commonly known as the "Swiss Embroidery-Machine," having special bearing with reference to those that are designed for embroidering handkerchiefs, &c., and hence relating particularly to the construction of the immediate attaching-frame carried by the tambour-frame.

The invention consists in the construction and combination of parts and details, as will be fully described and set forth hereinafter, and pointed out particularly in the claims.

Reference is to be had to the accompanying drawings, forming part of this specification, in which similar letters of reference indicate corresponding parts in all the figures.

Figure 1 is a front elevation of the Swiss embroidery-machine provided with my improvements. Fig. 2 is an enlarged cross-sectional elevation of parts of the same on the line *xx*, Fig. 1. Fig. 3 is a detail front view 30 of part of one of the frames for holding the pieces of fabric, a series of pieces of fabric being shown in said frame. Fig. 4 is a sectional plan view of the same on the line *yy*, Fig. 3. Fig. 5 is a cross-sectional elevation on the line *zz*, Fig. 4. Fig. 6 is a front elevation 35 of one of the frames for holding the pieces of fabric, the construction of the frame being slightly changed. Fig. 7 is a cross-sectional elevation of the same on the line *ww*, Fig. 6.

The embroidery-machine is of the usual well-known construction, and no parts of the carriages, the needle-holders on the same, the needle-releasing devices, the pantograph, or the mechanism for moving the cloth-holding frames, are changed. The metal frame A is suspended by the bars A', and the cross-pieces A² from rollers B, running on the top bar, C, of the frame D of the machine in the usual manner. The metal frame A is provided with the

two openings E E, or, if desired, only one; or three openings may be provided, as in the machines used heretofore, and at the edges of said openings the usual rollers, F, on which the fabric is secured, may be provided, or said rollers may be dispensed with. A greater or less distance below the top edge of each opening E in the metal frame A, a bar, G, is held by straps H, secured to the frame A and to the said bars, and on the under side of each bar G a bar, J, is secured, which is provided in its front and bottom with a rabbet, J'.

A short distance above the bottom edge of each opening E in the frame A, a bar, K, is held parallel with said edges, which bar has a rabbet formed in its top and front. The bars K are secured on the upper ends of the rods L, the lower rods L projecting down through flanges M on the front of the frame A, at the bottom edge of the lower opening E, and through guides N on the front of the frame 70 below said opening E. The lower ends of the lower rods L rest on the U-shaped springs P, resting and secured on a front flange, O', of the frame A. The upper rods L are guided by collars O' or other guides on the front of the 75 frame A.

In place of the U-shaped springs spiral springs P² may surround said rods L and rest against collars P' on the same, whereby the rods are forced upward. A series of 80 latches, Q, are pivoted to the front edges of the bars J and K, and serve to hold in place between said bars the frames R, in which the handkerchiefs S or other articles to be embroidered are held. Said frames are provided 85 with top and bottom bars, a b, having a T-shaped cross-section and fitting against the bars J and K in the manner shown in Fig. 2. The latches Q are then swung over the bars a b and hold them in place. The top and bottom bars, a and b, are united by V-shaped or U-shaped strips d, or by strips having a U-shaped or V-shaped longitudinal groove in the front surface. Into said V-shaped grooves or the recesses of the V-shaped pieces a clamping-bar, g, fits, which is provided with a rubber sleeve, h, throughout its length, or in place 95 of the rubber sleeve h a covering of any other

material producing great friction may be used; but I prefer to use rubber. The upper ends of the V-shaped bars project into recesses formed in the bottom surface of the top bar, *a*, and thus the upper ends of the clamping-bars *g* are prevented from leaving the V-shaped recesses. The lower ends of the bars *g* are held in place by keys *l*, or wedges passed into apertures in the bottom bars, *b*, in the front edges of the same; or said clamping-bars *g* may be held in place by latches or buttons *m*, pivoted on the front edges of the bottom bars, and adapted to be swung over the front edges of the clamping-bars. The bars *a* and *b* of the frames *R* are also united by rods *U*.

About midway between each pair of bars *d* a pin, *T*, projects from the upper surfaces of the bar *a*, which pins serve to hold the corners of the pocket-handkerchiefs, which are hooked on the same, and then stretched over the open edges of the bars *d*, and are held in the same by means of the clamping-bars *g*, which are forced into the grooves in said bars *d*, and then locked in place by either the latches or buttons *m'*, or the keys *l*. The rubber sleeves *h* prevent the slipping of the pieces of fabric. The edges of the pieces of fabric are then folded over, as shown near the section line in Fig. 4, and are then pinned together by means of the pins *m*. The frames *R*, on which the pocket-handkerchiefs or other pieces of fabric are held in the manner described, are then placed between the bars *J* and *K*, and the embroidery is produced in the corners of the handkerchiefs or pieces of fabric in the upper parts of the squares or rectangles formed by the bars *a* *b* and the V-shaped bars *d* uniting them.

In case the ornaments are to be produced in any other part of the handkerchiefs or piece of fabric, more pins *T* must be provided, or the pocket-handkerchiefs or pieces of fabric may be held in the frames in any other suitable manner.

To secure the frames *R* on the frame *A*, the bottom bars, *b*, of the frames are placed on the bottom bars, *K*, of the frame *A*, and said bottom bars, *K*, pressed down and the upper edges of the frames *R* are swung against the top bars, *J*, the latches or buttons *Q* being raised, and then said latches or buttons are swung over the top and bottom bars, *a* and *b*, which are thus held in place. The frames cannot be thrown out, as the bottom bars, *K*, are pressed against the bottom bars, *b*, of the frame by the springs *P* or *P'*.

My improved attachment can be applied on any embroidery-machine, and requires no further changes of the same than the fastening of the top bars, *J*, on the frame *A* and providing the bottom bars, *K*, and the springs acting on them.

Having thus fully described my invention, I claim as new and desire to secure by Letters

65 Patent--

1. The combination, with a Heilman or Swiss embroidery-machine of the usual construction, and provided with a frame, *A*, having openings, of bars held on said frame below the top edges of the openings, movable bars held in the openings of the frames short distances above the bottom edges of said openings, and the inner or fabric-carrying frame held between said bars, substantially as herein shown and described. 70

2. The combination, with a Heilman or Swiss embroidery-machine of the usual construction, and having a frame, *A*, provided with openings, of bars held in the openings below the top edges of said openings, bars 80 held at the bottom edges of the openings, and springs for pressing the bottom bars upward, and the inner or fabric-carrying frame held between said bars, substantially as herein shown and described. 85

3. The combination, with a Heilman or Swiss embroidery-machine of the usual construction, and having a frame, *A*, provided with openings, of bars held on the frame below the top edges of the openings, bars held 90 at the bottom edges of the openings, rods projecting downward from the lower bars, springs acting on said bars and pressing the lower bars upward, and the inner or fabric-carrying frame held between said bars, substantially as 95 herein shown and described.

4. The combination, with a Heilman or Swiss embroidery-machine having the usual frame, *A*, provided with openings, of fixed bars held below the top edges of the openings, 100 movable bars held above the bottom edges of the openings, springs for pressing the movable bars toward the fixed bars, which bars are rabbeted, buttons or latches pivoted on the bars for the purpose of holding frames on 105 said bars, and the inner or fabric-carrying frame held between said bars, substantially as herein shown and described. 110

5. The combination, with a Heilman or Swiss embroidery-machine of the usual construction, and having the frame *A*, provided with openings, of the fixed bars in one edge of each opening, movable bars at the opposite edges, and the inner or fabric-carrying frame held between said bars, substantially as herein 115 shown and described.

6. The combination, with a Heilman or Swiss embroidery-machine of the usual construction, and having the frame *A*, provided with openings, of fixed bars in one edge of each opening, movable bars at the opposite edges, bars for pressing the movable bars toward the fixed bars, and the inner or fabric-carrying frame held between said bars, substantially as herein shown and described. 120

7. Fabric-holding frames for embroidery-machines, consisting of top and bottom bars united by bars having grooves, clamping-pieces placed in said grooves, and provided with rubber sleeves, and of latches or buttons 125 130

for locking the clamping-pieces in place in the grooves, substantially as herein shown and described.

8. A frame for holding pieces of fabric in embroidery-machines, consisting of top and bottom bars united by grooved bars, clamping-pieces in the grooves, having rubber sleeves, latches or keys for holding the clamping-

pieces in place, and of pins projecting from the upper bar about midway between each pair of grooved bars, substantially as herein shown and described.
